United States Patent Office.

WILLIAM YOUNGBLOOD, OF NEW YORK, N. Y.

Letters Patent No. 77,701, dated May 5, 1868.

IMPROVEMENT IN HORSE-COLLAR.

The Schedule referred to in these Letters Patent and making part of the same.

TO ALL WHOM IT MAY CONCERN:

Be it known that I, WILLIAM YOUNGBLOOD, of the city, county, and State of New York; have invented a new and improved Horse-Collar; and I do hereby declare that the following is a full, clear, and exact description thereof, which will enable others skilled in the art to make and use the same, reference being had to the accompanying drawings, forming part of this specification, in which—

Figure 1 represents a perspective view of my invention.

Figure 2 is a horizontal sectional view of the same.

Similar letters of reference indicate corresponding parts.

The object of my invention is to provide a horse-collar which shall not be forced out of its proper shape by the action of the hames, when the animal is drawing a heavy load. The stitching in the groove of the ordinary leather collar soon becomes worn, and consequently gives way under a heavy strain upon the hames, rendering the collar useless. Tubular collars of India rubber have also been formed, and either filled in the ordinary manner, or the filling first set up in the desired form and coated with India rubber.

The exterior surfaces of these collars are of the usual form, but the interior surface bears at all points upon the filling, and particularly at the points where the hames are made to act. It follows, therefore, that any undue and varied strain upon the latter compresses the filling, bringing both sides of one arm of the collar together, destroying the filling, and forcing the collar out of its proper shape to such an extent as to render it useless.

My invention consists in providing a tubular India-rubber collar with a thick partition of the same material, extending longitudinally of said collar, and immediately beneath the bearing-surfaces of the hames. The collar is thus divided into two parts or tubes, each provided with a separate filling. The edge of the partition being brought immediately beneath the hames, cannot be compressed in any appreciable degree, and the filling cannot therefore be destroyed from the causes before mentioned.

A represents a horse-collar of ordinary exterior. It is made of one single piece of rubber, forming two tubes, a' b' , separated longitudinally by a thick rubber partition, a , for the purpose of strengthening that portion of the collar which is to receive the hames. The joint is either made by cementing the ends together, as at b in fig. 1, or they may be secured by copper rivets, or in any other suitable manner.

Having thus described my invention, what I claim as new, and desire to secure by Letters Patent, is—

As a new article of manufacture, an India-rubber horse-collar of tubular form, when said collar is divided longitudinally by the thick India-rubber partition a , forming an increased bearing-surface for the hames, as herein shown and described.

WILLIAM YOUNGBLOOD.
